APPARATUS FOR CASE HARDENING
GLASSRobert A. Miller and Lloyd V. Black, Tarentum,
Pa., assignors to Pittsburgh Plate Glass Com-
pany, a corporation of Pennsylvania

Application December 4, 1934, Serial No. 755,937

4 Claims. (Cl. 49—14)

The invention relates to apparatus for case hardening glass and particularly to the means for supporting the glass sheets during the heating and chilling operations. In an operation of this kind, 5 the glass is suspended in a vertical plane from its upper edge, ordinarily by clamps carried by a horizontal supporting bar, and in the case of large sheets difficulty is experienced in keeping the points of support in horizontal alignment in- 10 cident to the warping of the supporting bar caused by the extremes of temperature to which the bar is exposed. As a result, the horizontal edges of the glass sheets are distorted and made ir- 15 regular since the sheets are heated to a tempera- ture approximating the softening point, and the softening of the glass permits the distortion due to the very considerable weight of the glass. The object of the invention is to provide supporting 20 means which will overcome the difficulty as to distortion so that the upper and lower edges of the case hardened sheets are substantially straight and free from distortion. Briefly stated, the de- 25 sired object is accomplished by making the sup- porting bar in sections, each supported for free independent movement, and by providing means for preventing the hangers which support the bars from being warped out of alignment. One em- 30 bodiment of the invention is illustrated in the accompanying drawings, in which:

Figure 1 is a side elevation. Fig. 2 is a partial section and partial end view. And Fig. 3 is a section on the line III—III of Fig. 1.

Referring to the drawings, 1 is the furnace through which the glass sheets are carried in 35 order to heat them preliminary to the chilling operation, such furnace being provided with a slot 2 along its upper end; and 3 is a monorail extending longitudinally of the slot there- above. This monorail carries a pair of trolleys 4 and 5 having the wheels 6, which ride on the flanges of the rail. These trolleys carry a rigid frame made up of the angles 7, 7 and from this frame depends the series of hangers 8, 8, 8 adapted to extend through the slot 2, as indicated in Fig. 40

2. Asbestos sheets 9, 9 carried by the top of the furnace serve as a closure for the slot 2 and yet permit the ready passage of the hangers.

The lower portion of each hanger is made up 45 of a pair of plates 10, 10 bolted or riveted to the lower ends of the member 8 and spaced at their lower ends by the pairs of blocks 11 and 12 se- 50 cured by the bolts 13 and 14. Extending through the hangers between the plates 10, 10 and resting on the blocks 13 is a stiffening bar 15. This bar 55 is free to move endwise with respect to each of

the hangers and serves to keep them in alignment and prevent any warping of the hangers which would tend to throw them out of alignment.

Supported upon a series of blocks 12 at the ex- 5 treme lower ends of the hangers are the tong bars 16 and 17. These tong bars are each free to move easily in an endwise direction through the hangers, the opposing ends of the bars 16 and 17 being spaced in the middle hanger, as indicated at 18. This freedom of movement reduces the 10 tendency of the bars to warp, and in order to still further reduce this tendency, the bars are slotted, as indicated at 19. Each of the tong bars carries a series of collars or loops 20 to whose lower ends are attached the links 21 (Fig. 2). 15 These links are attached at their other ends to the handle 22 of the tongs 23, such tongs being provided with the usual pins 24 for engaging the edge of the glass sheet. The weight imposed by the glass sheet tends to close the tongs and thus 20 give the necessary gripping action upon the edge of the sheet.

The use of the supporting means for the glass sheets, as illustrated and described, gives a sup- 25 port which even with very large sheets avoids any substantial deformation of the upper and lower edges thereof. Any vertical warping in the tong bars is reduced to a minimum incident to their relatively short length and their freedom to expand, and the stiffening bar 15 prevents any 30 lateral deformation of the edge of the sheet, as the hanger plates 8 are maintained by this expedient in substantial alignment at all times. The support 1, 1, to which the upper ends of 35 the hangers are attached, lies well outside of the heat of the furnace so that this member is not subject to deformation.

In operation, the glass sheet is supported upon the apparatus outside the furnace and is then 40 moved along through the furnace which is in the form of a tunnel kiln of gradually increasing temperature. When the glass has reached a proper temperature for chilling, it is removed through the outlet end of the furnace, the general 45 operation being well known in the art.

What we claim is:

1. Apparatus for case hardening glass sheets comprising a longitudinally extending overhead support, a series of spaced hangers depending 50 from the support, a series of supporting bars placed end to end and supported at each end in one of the hangers so that such ends are free to move through the hangers, and a plurality of spaced gripping members carried by each bar and 55

adapted to engage the edge of the glass sheet which is to be case hardened.

2. Apparatus for case hardening glass sheets comprising a longitudinally extending overhead support, a series of spaced hangers depending from the support, a series of supporting bars placed end to end and supported at each end in one of the hangers so that such ends are free to move through the hangers, and a plurality of spaced gripping members carried by each bar and adapted to engage the edge of the glass sheet which is to be case hardened, said bars each being notched on its upper and lower sides.

3. Apparatus for case hardening glass sheets comprising a longitudinally extending overhead support, a series of spaced hangers depending from the support, a series of supporting bars placed end to end and supported at each end in one of the hangers so that such ends are free to move through the hangers, a horizontal stiffening bar extending the length of the series of hangers above such bars and engaging such hangers and holding them in alignment but free to move end-

wise with respect thereto, and a plurality of spaced gripping members carried by each supporting bar, and adapted to engage the edge of the glass sheet which is to be case hardened.

4. Apparatus for case hardening glass sheets comprising a longitudinally extending overhead support, a series of spaced hangers depending from the support, and each comprising a pair of parallel plates having supporting abutments at their lower ends, a series of supporting bars placed end to end and supported at each end in one of the hangers on said abutments so that such ends are free to move endwise on the abutments, a horizontal stiffening bar above the supporting bars extending between the plates comprising the hangers and supported thereby but free to move endwise with respect to the hangers, and a plurality of spaced gripping members carried by each supporting bar, and adapted to engage the edge of the glass sheet which is to be case hardened.
